UNITED STATES PATENT OFFICE

90,795

DESIGN FOR A MEMORIAL PLATE MARKER

John A. Atchley, Reece E. Atchley, and Edward H. Collins, Kansas City, Mo.

Application July 31, 1933. Serial No. 48,882

Term of patent 7 years

To all whom it may concern:

Be it known that we, JOHN A. ATCHLEY, REECE E. ATCHLEY, and EDWARD H. COLLINS, citizens of the United States, residing at Kansas City, Jackson County, Missouri, have invented a new, original, and ornamental Design for a Memorial Plate Marker, of which the following is a specification, reference being had to the accompanying drawing forming a part hereof.

In the drawing:—

We claim:—

The ornamental design for a memorial plate marker as shown.

JOHN A. ATCHLEY.
REECE E. ATCHLEY.
EDWARD H. COLLINS.
